UNITED STATES PATENT OFFICE.

DAVID JOHNSTON MACDONALD, OF DUNDEE, SCOTLAND.

NEEDLE-LOOM.

SPECIFICATION forming part of Letters Patent No. 643,878, dated February 20, 1900.

Application filed November 1, 1899. Serial No. 735,620. (No model.)

To all whom it may concern:

Be it known that I, DAVID JOHNSTON MACDONALD, a subject of the Queen of Great Britain and Ireland, and a resident of Dundee, Scotland, have invented certain new and useful Improvements in and Connected with Needles for Looms, (for which I have applied for British Letters Patent No. 7,763, dated April 13, 1899,) of which the following is a specification.

My said invention relates to wefting mechanism of the kind in which the weft is drawn off a bobbin or roll separate from the loom; and it comprises improvements in or modifications of details of the mechanism described in my Patent Specification No. 633,020, dated September 12, 1899.

My present improvements relate to the arrangement of a selvage-shuttle and the mechanism for actuating the same, also to appliances for taking up the slack of the weft and for controlling its tension.

In order that my said invention and the manner of performing the same may be properly understood, I hereunto append two sheets of explanatory drawings, to be hereinafter referred to in describing my improvements.

Figure 1 is a plan, and Fig. 2 a sectional front elevation, of parts of a loom, sufficient to show the application of my improvements. Figs. 3, 4, and 5 are enlarged views of the mechanism for actuating the selvage-shuttle. Figs. 6, 7, 8, and 9 are enlarged views of the shuttle and its carrier, and Fig. 10 is an enlarged view of the weft take-up and controlling appliances.

In the drawings the same reference-letters are used to mark the same or like parts wherever they are repeated.

The warp-shedding apparatus of the loom may be the same as in existing looms, and it is unnecessary to complicate the drawings by showing it.

In carrying out my present invention the wefting mechanism is the same as that described in my earlier specification hereinbefore referred to; but instead of the arrangement of selvage-shuttle described in that specification I employ an oscillating shuttle similar to what is used in some kinds of sewing-machines. This shuttle A, Figs. 6 and 7,

is hollow and is made with a central tube A', on which turns a spool B for the selvage-thread. (Not shown.) A spiral spring A², placed in the tube A', presses on one end of a tension-finger B', hinged to the tube A', so as to cause the other end to bear on the flange of the spool B when it is in the shuttle A, and thus apply the requisite tension to the thread. The degree of tension may be regulated by adjusting a small screw B², inserted from the opposite side of the shuttle A, so as to cause the screw B² to bear more or less on the spring A². To get the spool B into the shuttle A, the tension-finger B' is turned into the position shown by dotted lines in Fig. 7. The shuttle A is made with two hooks or projections A³ A⁴, with which engage two pins C' C² on a driving-carrier C, Figs. 8 and 9, in the form of a disk having a spindle C³. The shuttle A, with its carrier C, is held in a case D, Figs. 3, 4, and 5, fixed to the lathe D', the spindle C³ projecting through one side of the case and having on its outer end a bevel-wheel D², which gears with a bevel-wheel D³ on the upper end of a vertical spindle E, carried by the lathe D'. The vertical spindle E has on its lower end a pinion E', gearing with a spur-wheel E², which is on a stud E³ and which has an eccentric-pin F projecting down from it and carrying an antifriction-roller which is acted on by a cam-slot F' in a plate F², fixed to the breast-beam F³. As the lathe D' moves forward and backward the gearing and slotted plate hereinbefore described cause the shuttle A to oscillate or reciprocate angularly in the required manner, so that the hook A³ on the shuttle A, which projects through an opening in the front of the case D, will engage in the loop of weft passed through and emerging from the shed, as described in my earlier specification hereinbefore referred to.

In order to prevent the outer thread or side of the weft-loop from being improperly acted on by the shuttle A, there descends into the loop (just before the shuttle carries the inside thread of the loop around) a vertical finger G, which is D-shaped near the point, this D-shaped part keeping back the outer thread of the loop until the slack of the weft requires to be taken up, as hereinafter described, when the finger G rises clear. The

vertical finger G slides in a guide G', formed for it in the front of the lathe D', the upper end of the finger being forked and carrying an antifriction-roller G², which runs on a 5 cam-shaped guide-bar G³, fixed to the breast-beam F³, so that as the lathe D' moves the finger G will rise and fall, as described.

The appliances for taking up the slack of the weft and for controlling its tension are 10 shown more fully in Fig. 10. The weft H passes from the bobbin or roll H' up to and over a guide-bar H², on which it is pressed by a weighted tension-lever H³. The weft H proceeds thence to a guide-eye J in the bottom of one leg of a vertical slotted or two-legged stationary bar J', and between the two 15 legs it passes through a guide-eye J² in a piece J³, which slides between the legs and has on it an antifriction-roller J⁴. The weft passes from the guide-eye J² to a guide-eye J⁵ in the 20 bottom of the other leg of the bar J'. The roller J⁴ is in a cam-shaped guide-slot K in a bar K', fixed to and projecting back from the lathe-rail D', and as the lathe beats up the 25 slot K in the bar K' raises the sliding piece J³ in the slot of the stationary bar J' and takes up the slack of the weft H. At the same time a cord K², attached to the sliding piece J³ and passing over guide-pulleys K³ K⁴, becomes 30 slack and allows the weighted tension-lever H³ to bear fully on the weft H, thus insuring that while the slack of the weft is being taken up additional weft is prevented from being drawn from the supply at the back. 35 When the lathe D' moves back, the cord K² is tightened, so as to lift the weighted tension-lever H³ and allow the weft to be drawn with diminished tension. The weft H passes onward from the guide-eye J⁵ in the stationary 40 bar J' to a guide-eye in a small block L, fitted to slide on a vertical rod L', fixed to the back of the lathe D', and thence to the wefting mechanism described in my earlier specification, hereinbefore referred to. This sliding guide L by its weight bears down slack 45

weft and prevents it from looping and becoming entangled.

This improvement is of advantage in weaving narrow fabrics.

What I claim as my invention is—

1. In connection with wefting mechanism for looms, the combination of a lathe, an oscillating selvage-shuttle having a hook or projection, a driving-carrier therefor and a containing-case fixed to the lathe, with a stationary cam-plate and gearing connecting said carrier with the cam-plate to cause the shuttle to oscillate by the backward-and-forward movement of the lathe, substantially as described. 50

2. In connection with wefting mechanism for looms, the combination of a lathe, an oscillating selvage-shuttle having a hook or projection, a driving-carrier therefor and a containing-case fixed to the lathe with means 55 for oscillating the shuttle by the backward-and-forward movement of the lathe and a moving finger G to engage the weft-loop, substantially as described. 60

3. In needle-looms, appliances for taking up the slack of the weft and for controlling its tension, consisting of a guide-bar for the weft, and a weighted tension-lever bearing on the weft passing over the bar, in combination with a two-legged stationary bar having 70 guide-eyes in their lower ends and a sliding piece working between the legs, the sliding piece having in it a guide-eye, a cord connecting the sliding piece to the weighted tension-lever, and the lathe having a cam-bar to 75 act on the sliding piece, and also having a vertical rod with a sliding guide-eye, all substantially as herein set forth. 80

In testimony whereof I have signed my name to this specification in the presence of 85 two subscribing witnesses.

DAVID JOHNSTON MACDONALD.
